United States Patent Office

Des. 177,554
Patented May 1, 1956

177,554

FINGER RING

Melvin V. Chevers, Plainville, Mass., assignor to Southern Methodist University, a corporation of Texas

Application November 1, 1955, Serial No. 38,675

Term of patent 14 years

(Cl. D45—10)

Fig. 1.

Fig. 2.

Fig. 3.

Fig. 1 is a top plan view of a finger ring showing my new design;

Fig. 2 is an elevational view looking at one side;

Fig. 3 is an elevational view looking at the other side.

I claim:

The ornamental design for a finger ring, substantially as shown.
